Specification for Design.

Patented Oct. 11, 1921.

Application filed October 13, 1919. Serial No. 330,497. Term of patent 14 years.

To all whom it may concern:

Be it known that I, FRANK W. ANDREWS, a citizen of the United States, residing at Wapakoneta, in the county of Auglaise, State of Ohio, have invented a certain new and original Design for a Fire-Extinguisher, of which the following is a specification, reference being had to the accompanying drawing, forming a part thereof.

The figure is a perspective view of a fire extinguisher showing my new design.

I claim:

The ornamental design for a fire extinguisher, as shown.

In testimony whereof, I have hereunto set my hand this 26 day of July A. D. 1919.

FRANK W. ANDREWS.
